OPHTHALMIC MOUNTING

John N. Nelson, Providence, R. I., assignor to
Universal Optical Corporation, Providence,
R. I., a corporation of Rhode Island

Application October 16, 1929, Serial No. 399,969

2 Claims. (Cl. 88—43)

This invention relates to an improved construction of ophthalmic mounting and has for its object to provide a bridge member connecting the lens-engaging members, the bridge having 5 rearwardly extending side arms of a substantial length adapted to be bent laterally for adjusting the pupillary distance between the lenses.

A further object of the invention is to also attach a pair of nose-guards to the lens-engaging 10 members, each thru a rearwardly-extending bendable arm whereby they may be adjusted independently of the bridge adjustment to so engage the nose as to properly support the mounting on the face of the wearer.

15 The invention further consists in positioning the nose-guard so that a portion of the guard plates extend into proximity of the return bend in the bridge arms to partially hide the same and present the appearance of being a part 20 thereof.

With these and other objects in view, the invention consists of certain novel features of construction, as will be more fully described, and particularly pointed out in the appended claims.

25 In the accompanying drawing:

Figure 1 is a front view showing one form of my improved ophthalmic mounting.

Figure 2 is a side elevation partly in section showing one of the eyewires with a portion of the 30 bridge connected thereto.

Figure 3 is the same as Figure 2 with addition of the nose-guard also connected with the eyewire.

Figure 4 is a perspective view showing the 35 bridge and the nose-guard connected to the eyewire.

Figure 5 is a detailed construction of the bridge with a return bend at its ends with side arms of a substantial length.

40 Figure 6 is a detail of the nose-guard having a rearwardly extending bendable arm to be attached to the lens-engaging member.

Figure 7 is a top view showing the side arms of the bridge of extended length and connected to the eyewires or lens-engaging members.

45 Figure 8 is the same as Figure 7 and showing the side arms as having been bent outwardly and to extend the pupillary distance between the lenses.

50 Figure 9 is a modification illustrating the bridge and the nose-guard as connected to a lens-engaging member in the form of a lens clamp instead of an eyewire.

It is found in practice that where the old style 55 of ophthalmic mounting having temples utilizes

a bridge to support the frame on the nose of the wearer, that many sizes have to be carried in stock for each different design of mounting, in order to fit the widely varying shapes of faces of the different wearers and where these metal 60 frames are made of precious metals a considerable investment is required to carry a full line of these mountings, and in order to obviate the necessity of carrying so large a stock, I have constructed the mounting in such a way that it 65 may be readily adjusted over quite a wide range and so reduce to a great extent the number of mountings required to be carried in stock, and to accomplish this I have formed a bridge member with a return bend at its ends thus providing 70 side arms of a substantial length adapted to be bent laterally or toward and from each other to adjust the pupillary distance of the mounting. Also, I have mounted a guard member independent of the bridge member having an arm 75 connected preferably to the lens-engaging member independent of the bridge member, whereby this guard member may be adjusted independently of the adjustment of the bridge to properly support the mounting on the nose of the 80 wearer; and the following is a detailed description of the present embodiment of my invention and showing one means by which these advantageous results may be accomplished:

With reference to the drawing 10 designates 85 the lenses and 11 one form of lens-engaging member which in this instance is an eyewire; the eyewires are connected together by a bridge member 12. This bridge member is herein shown as being positioned on an incline relative to the 90 plane of the eyewires, the forward portion of the bridge being substantially flush with the forward edges of the eyewires and the bridge extending rearwardly and downwardly and its ends provided with a return bend as at 13, forming 95 side arms 14 of substantial length which are attached by solder or otherwise to the lens-engaging members 11.

By this construction these side arms as best 100 illustrated in Figures 7 and 8 may be bent laterally either inwardly or outwardly to regulate the pupillary distance between the lenses to accommodate the faces of different wearers.

The bridge in this case serves only as a connector between the eyewires. 105

In order to provide a support for the mounting independent of the bridge, I have formed a pair of nose-guards 15 each of which has a bendable arm 16 which extends forwardly and 110

is connected by solder or other suitable means to the eyewire.

The upper portion 17 of the plate of each guard is arranged to extend into close proximity to the 5 return bend 13 of the bridge so as to partially hide the bend and present the appearance of being connected thereto, and in some cases the guard may be connected to the bridge.

By this construction of forming the nose-guard 10 separate and independent of the bridge, it will be seen that they may be adjusted independently of the bridge adjustment to engage the nose of the wearer and support the mounting in the proper position on his face, that is, in other words, 15 the bridge serves to permit a wide adjustment of the pupillary distance between the lenses and the guards serve to support the mounting in proper position on the nose of the wearer.

By this adjustment the number of different 20 sizes of mountings may be greatly reduced, thus materially reducing the investment of the dealer in these mountings, which is of considerable importance particularly where the mountings are 25 of precious metals and also by this independent adjustment it permits more accurate fitting of the mountings to the faces of the different wearers.

The foregoing description is directed solely towards the construction illustrated, but I desire it 30 to be understood that I reserve the privilege of resorting to all the mechanical changes to which the device is susceptible, the invention being defined and limited only by the terms of the appended claims.

I claim:

35 1. In an ophthalmic mounting, two lens mem-

bers, a relatively rigid deformable wire bridge connecting the lens members and having the central portion thereof concavo-convex along its length, the portions of the wire on either side of the crest being rounded and extending rearwardly and downwardly and folded upon themselves and extending forwardly with each of the folded portions in a plane which is substantially vertical and at a right angle to the plane of the lenses, and with the forwardly-extending portion spaced from the rearwardly-extending portion and bendable relatively thereto, the ends of said forwardly-extending portions rigidly connected to the lens members and approaching said members at substantially right angles to the plane of said lenses. 90

2. In an ophthalmic mounting, two lens members, a relatively rigid deformable wire bridge connecting the lens members and having the central portion thereof concavo-convex along its length, the portions of the wire on either side of the crest being rounded and extending rearwardly and downwardly and folded upon themselves and then extending forwardly with each of the folded portions in a plane which is substantially vertical and at a right angle to the plane of the lenses 100 and with the forwardly-extending portion spaced from the rearwardly-extending portion and bendable relatively thereto, the ends of said forwardly-extending portions rigidly connected to the lens members and approaching said members at substantially right angles to the plane of said lenses, and an independent nose guard plate having a rearwardly-extending arm bent in an S curve and doubled back upon said plate. 105
